UNITED STATES PATENT OFFICE

GEORGE E. BRITTAINE, OF LYNN, MASSACHUSETTS, ASSIGNOR TO LOUIS H. HARRIMAN,
OF HAVERHILL, MASSACHUSETTS, AS TRUSTEE

SHOE COUNTER

Application filed April 4, 1928. Serial No. 267,278.

This invention relates to certain improvements in shoe counters, or heel stiffeners, which are moulded in U-form from sheet material, usually stiff leather, leather board, or fiber board, and which are, also, of the type in which both sides of the counter extend beyond the heel breast for a substantial portion of, or the greater portion of the length of the shank part of the shoe, counters of this type being very generally used in that class of shoes for women known as pumps or slippers, although they may be advantageously employed in shoes of other type.

In lasting shoes in which counters of this description are employed, much difficulty has been encountered in making the counter conform to the last at all points at which it is designed to be held in close contact therewith, for reasons explained to some length in my prior Patent No. 1,636,982, in which a construction is disclosed which overcomes this difficulty to some extent in that it enables the front end portions of the counter to be conformed to the inclined shank portions without causing the counter to be pushed back away from the heel end of the last. However, as lasts are ordinarily now constructed, the sides thereof, adjacent the bottom, converge from points adjacent the middle of the sides of the heel as they extend towards the middle of the shank, the extent of the inclination towards the middle line at the inner side of the last being substantially greater than that at the outer side. In molding counters by the methods ordinarily employed, the inturned flange is molded flat and the sides are molded so that they are parallel from the points above referred to, at the middle of the sides of the heel, to the front ends thereof. Consequently the lines of the vertex of the angle between the sides and the flange, at each side, are parallel to each other from the middle of the heel to the front ends of the side portions, and do not curve inward from these points,

as do the lines of the corresponding edges of the sides at the bottom of the last, said sides usually extending divergently from points adjacent the middle of the shank to the ball, the extent of this divergence from the middle line being somewhat greater at the inner side than at the outer side. On account of the approximately right angular formation of the counter at the junction of the flange and sides, the counter is very inflexible along the line of the vertex of this angle, so that it is very difficult to bend the counter inward sufficiently from the line in which it is moulded, to force the inner vertex of the angle into coincidence with the outer corner of the edge of the innersole, which will have been secured to the last before lasting, throughout the entire length of the counter side portions. Consequently, while the counter may be forced into approximate conformity with the last, it is difficult to do this at both sides thereof, and usually results in a failure of the counter to fit closely to the last at its inner side near the bottom at points in front of the middle of the heel. Also, in some instances, the formation of the last is such that, when the counter, as molded, is placed thereon, the flange at one side engages the bottom of the innersole and does not engage at the other by reason of the fact that the outer side of the heel seat of a last is frequently built up more than at the inner side, so that the heel seat is not level transversely but is somewhat inclined. In consequence, the flange portion at the outer side of the last will hold the flange portion at the inner side thereof away from the last bottom or inner sole surface and difficulty is encountered under such conditions in forcing the angular portion of the counter inward or downward, at the inner side, sufficiently to bring the flange throughout its entire width into firm contact with the bottom, and if this is not done, the top edge of the counter will be lower at the inner side

than at the outer side. Failure to force the angular portion of the counter into position, so that the side thereof engages the edge of the innersole, also results in serious well known shoe making defects, as does almost any lack of conformity of the counter with the last at the time of the lasting operation.

The difficulties above referred to may be practically entirely obviated by molding the counters in rights and lefts, but this involves a very large increase in the cost of producing the counters, due principally to the very large increase in the number of moulding dies necessary to their production, as compared with the dies necessary to produce the usual straight sided counters. For this and for various other reasons, the increased cost of right and left counters is so great as to be considered prohibitive in many instances.

The primary objects of my invention are to provide a molded shoe counter which may be formed from stiff leather or fiber board and may be conformed without difficulty to either a right or a left last of the types above referred to, after having been molded on dies of the formation usually employed for the ordinary type of counter, and which is so constructed that it may be flexed without difficulty by the laster, when performing the usual lasting operation, along the line of the vertex of the angular formation between the flange and the sides, at each side thereof, so that these portions may be forced into practically perfect conformance with the last at the edge of its bottom from points at the middle of the side of the heel seat to the front ends of the sides of the counter, even if they are extended throughout practically the entire length of the shank part, and to accomplish these results without objectionable increase in the manufacturing cost of the counter and without impairment of its strength or effectiveness as a stiffener for the heel and shank portions of the shoe.

I accomplish these objects, primarily, by forming in the counter blank before it is molded a series of slits therein which extend transversely of the line of the vertex of the angle between the flange and the sides of the counter but terminate short of the edges of the blank, and more particularly by forming the slits by cuts which extend obliquely to the surface of the counter in lines which are oblique to the lines of the said vertex, as hereinafter more particularly described.

For a more complete disclosure of my invention, reference is made to the following specification, in connection with the accompanying drawing in which:

Figs. 1, 3 and 4 are plan views of a counter blank showing different stages in the process of manufacture.

Fig. 2 is a sectional view at line 2—2 of Fig. 3 indicating a step in the process.

Fig. 5 is a bottom plan view of the finished molded counter.

Fig. 6 is a bottom plan view and Fig. 7 is a perspective view of the counter when placed in position on the last.

Figs. 8 and 9 are enlarged detail views of portions of the counter.

Fig. 10 is a similar view showing a modification.

Figs. 11 to 14 are detail sectional views illustrating other modifications, Figs. 11 and 13 being sections at lines 11—11 and 13—13 of Figs. 12 and 14, and

Figs. 12 and 14 being sections at lines 12—12 and 14—14 of Figs. 11 and 13, respectively.

In producing a counter embodying the present invention a blank, as *a*, is first died out from sheet material in the ordinary manner and in identically the shape previously employed, this operation being performed while the stock is in temper.

According to my invention the next operation consists in cutting a series of slits *b* thru the blank in transverse relation to the line 2—2 of Fig. 3, along which the bottom edge portion of the counter is bent inward to form the usual bottom flange, said slits being approximately bisected by said line 2—2, so that they extend to equidistant points therefrom, and being of such length that they terminate at their ends next the edge which is later to form the edge of the bottom flange, at points approximately midway between the edge and said line.

In forming said slits, two separate gangs of arc shaped knives *k* are preferably provided, which are held in parallelism and moved longitudinally by suitable means in predetermined oblique relation to the surface of the counter, which will be held flat on a suitable bed. As indicated in Fig. 2, in performing this operation the blank will be held on the bed horizontally with the side thereof uppermost which is to be the outer side of

the counter, and the knives *k* will be held at an acute angle, preferably about 30°, to the horizontal and be arranged in two reciprocally mounted gangs, one for each side portion of the counter, each gang being held in directly opposite relation to the other, so that they may be moved downward and towards each other, or towards the middle of the counter, to perform the cutting operation, and form the slits *b* in the blank which will be inclined in the same manner. The cutting edges of the knives *k* are each formed on an arc, which may approximate to a semi-circle, but which is preferably somewhat less than a semi-circle, the arrangement of the knives being such

that the concave side of the cutting edge of each knife faces towards the middle of the blank. As a result a series of curved, inclined slits will be formed in each half portion of the blank, as indicated in Fig. 3, which are so arranged that the convex sides

of the slits of each series face towards the end of the blank which is adjacent thereto and the inclination of the face of severance of each slit is such that each face extends towards the middle of the blank as it extends from the outer to the inner side thereof.

It may therefore be considered that two series of tongues *c* are formed on the outer side of the blank, each of which has a curved end and is undercut or beveled on its under side to form a sharp edge, the tongues of each series extending from the middle towards the adjacent end of the blank. These tongues do not, however, project outward from the outer surface of the blank, but lie flat thereon, or are made to do so by subsequent operations.

The next operation is what is known as the "clam shelling" operation, in which the blank is rolled into a somewhat curved, dished form, as indicated in Fig. 4, so that its insertion between the dies of the molding machine may be more easily accomplished. By this operation the slits *b* are opened, slightly at their outer ends, that is, the dishing operation causes the surfaces, formed by making the slits, to slide slightly one on the other, so that the outer edges of the slits do not exactly coincide, as indicated in Figs. 4 and 8.

The next and final operation in the formation of the counter is the usual molded operation in which the blank is molded into U-form and its edge portion is bent inward, along line 2-2, to form the bottom flange *d*, which is molded flat and at approximately right angles to the sides *e*, which extend in parallelism from the heel end, as indicated in Fig. 5.

The performance of this operation is materially facilitated by reason of the slits, which greatly increase the flexibility of the material. In addition to the slits *b* which are formed in the portions of the sides which are adapted to extend in front of the heel, two slits *b'* are preferably formed at points adjacent and equidistant from the middle of the counter, or in such positions that, when the molding operation has been performed, these slits will be located approximately midway between the middle of the back of the heel portion and the points adjacent the middle of the sides of the heel, from which the sides of the counter extend in parallelism. The formation of the slits *b'* at these points is primarily advantageous in reducing the strain on the molding machine, as all counters practically conform to the back half of the heel of the last when applied thereto. The bending of the blank at the heel end tends to open the outer ends of the slits *b'* slightly, as indicated in Figs. 5 and 8, but the pressure of the molding dies flattens the tongue portions formed by all of the slits, so that the latter are practically indiscernible. The action of the molding dies on the sides of the counter

includes a drawing action towards its ends of the counter, and this action tends not only to close the slits, but also to elongate the tongues formed thereby to such an extent that the latter slightly overlap the material at the opposite sides of the slits. As a result, to the casual observer, the slits are practically obliterated in the finished counter.

The number and location of the slits *b* may be varied according to circumstances and expediency. For example, they may be advantageously employed not only in the approximate locations indicated in full lines in the drawings, but also at points between the breast end of the heel seat and the middle of the heel seat, and also close to the extreme ends of the sides, as indicated in dotted lines in Figs. 6 and 7.

The formation of the slits across the line of the vertex of the angle between the flange and sides results in a greatly increased flexibility of the counter along this line, so that, when the counter is placed in position on the last, the portions along this line may be readily pressed inward until the outer corner of the innersole on the last is engaged by the inner vertex line of the counter throughout its length, as indicated in Figs. 6 and 7. This inward bending begins to take place at points adjacent the middle of the heel, at which points the sides *e* begin to diverge from the last, before the counter is bent from its molded formation, and continues throughout the rest of the length of the sides. The extent to which a side is bent inward along the vertex line depends primarily on whether it has been placed on a right or a left last. In conforming a side to the inward curvature of the edge of the inner sole, from the front portion of the heel to the front portion of the shank, by pressing the vertex portion of the corresponding part of the counter inward, the tendency will be for the tongue portions *c* to override the portion of the material directly in front thereof, as indicated in Fig. 9. While it is usually less difficult to conform the counter, at the vertex of the angle, to the outer edge of the innersole than to the inner edge thereof, some inward bending along the outer vertex line is usually necessary, so that the formation of the slits in both side portions of the counter is advantageous, aside from the fact that they enable any counter to be readily used either for a right or a left shoe.

The arc shaped formation of the slits is not essential, as other forms, in which the opposite portions thereof extend obliquely to the line 2-2, may be equally effective, for example, an equally effective form is illustrated in Fig. 10, in which the slits *b'* are of V-formation, the vertex of the V being somewhat rounded.

While the slits have been described as cut completely thru the material and while this

formation may be preferable, the advantages of my invention will be sufficiently secured by cutting the slits only part way therethru, and by forming such slits either on the outer or inner side of the counter in the locations above specified, such construction being shown in Figs. 11 to 14.

In Figs. 11 and 12 the formation of V-shaped slits b^3 on the inner side of the counter is indicated, said slits being cut at an inclination to the counter surface along the vertex line as before described, but cut at such a depth that they do not emerge at the outer side of the counter. In this instance it is immaterial whether the portions of the slits at each side of the vertex line converge as they extend towards the middle of the counter, or towards the end of the side in which they are located, for the reason that, in performing the molding operation, there is no drawing or sliding action on the inner side of the counter which would tend to turn back the tongues formed by the converging slit portions.

In conforming the angular portion of the counter to the inward curve of the edge of the shank part of the innersole and last, when the slits are formed on the inner side of the counter, the inward bending of this portion of the counter would tend to open the inner ends of the slits, as indicated in Fig. 11. The degree of flexibility which is secured by the formation of the slits b^3 would be practically the same as if the slits extended entirely thru the counter.

In Figs. 13 and 14 the formation of slits b^4 , which open to the outer surface of the counter, but do not extend entirely therethru, is illustrated. In this instance the cuts forming the slits are made the same as illustrated in Figs. 2 and 3 or 10, except that they are not extended entirely thru the material.

The action in use is also similar to that previously described, as, when the slitted portions are pushed downward and inward to bring the vertex of the angle between the flange and side into coincidence with the corner of the bottom of the last or innersole thereon, the tongues formed by the slits b^4 will override the adjacent portions of the material, as indicated in Fig. 13.

The effectiveness of the counter as a support for the upper and shank of the shoe is practically in no way impaired by the formation of the slits, whether they are extended entirely thru the material, or only partly therethru. The particular formation of the slits is important for several reasons, aside from their particular location in the counter. It is important that they do not extend to edge of the flange, as the flange would thus be weakened and be liable to be torn by the lasting pincers, also that they be formed to extend obliquely to the surface and that their opposite portions be oblique to the vertex line, as the pliability is increased without sub-

stantially reducing the strength. Moreover, a cut perpendicular to the surface or in a straight line, particularly if nearly perpendicular to the vertex line, would probably cause the material to crack beyond the ends of the cut, so that the sides of the counter would be so weakened as to break transversely.

The formation of the slits in a manner to provide under cut tongues is also important, as sliding movement thereof on the adjacent surfaces, when the angular portion is pressed inward, is readily permitted. The direction in which the tongues extend in each side portion is important on account of the necessary drawing action of the molding dies, except when the tongues are formed on the inner side of the counter, but in all the forms the tongues should extend in the direction of the vertex line, so that the middle line of the tongues approximately coincides therewith.

The formation of the slits, as described, not only enables the angular portion of the counter to be readily conformed to the inward curvature of last and innersole in front of the middle of the heel at each side, but enables the use of material in the manufacture thereof which is much stiffer, or more inflexible than would otherwise be possible.

As a counter, constructed as above described may be closely conformed to the last and innersole throughout the concave portions thereof and its adjacent flange portion may be held in firm engagement throughout the width thereof, with the sole bottom, the appearance of the shoe may be thereby improved and the top edges of the counter may be held at a uniform level at each side of the shoe. Moreover, all the advantages of counters which are molded as rights and lefts, to fit the last accurately, are secured, without the disadvantages of greatly increased cost of production and of other well known disadvantages incident to their use.

I claim:

1. A shoe counter of sheet material moulded in U-form to fit the heel end of a last and having its sides arranged to extend opposite the shank portion of a shoe and one edge portion thereof inturned to form a bottom engaging flange, each side portion of the counter having a plurality of suitably spaced slits cut therein across the line of the vertex of the angle between said sides and flange, said slits terminating in the material at each side of said line.

2. A shoe counter of sheet material moulded in U-form to fit the heel end of a last and having its sides arranged to extend opposite the shank portion of a shoe and one edge portion thereof inturned to form a bottom engaging flange, each side portion of the counter having a plurality of suitably spaced slits cut therein across the line of the vertex of the angle between said sides and flange,

said slits terminating in the material at each side of said line at points approximately equidistant therefrom.

3. A shoe counter of sheet material moulded in U-form to fit the heel end of a last and having its sides arranged to extend opposite the shank portion of a shoe and one edge portion thereof inturned to form a bottom engaging flange, each side portion of the counter having a series of slits cut therein at intervals across the line of the vertex of the angle between the sides and flange in oblique relation to said line and terminating within the material adjacent said line at each side thereof.

15 4. A shoe counter of sheet material moulded in U-form to fit the heel end of a last and having its sides arranged to extend opposite the shank portion of a shoe and one edge portion thereof inturned to form a bottom engaging flange, the side portions of the counter having a series of suitably spaced slits cut therein across the vertex of the angle between the sides and flange, said slits being terminated within the material adjacent the line of said vertex at each side thereof and having their opposite portions oblique to said line.

25 5. A shoe counter of sheet material moulded in U-form to fit the heel end of a last and having its sides arranged to extend opposite the shank portion of a shoe and one edge portion thereof inturned to form a bottom engaging flange, each side portion of the counter having a plurality of suitably spaced slits cut therein across the line of the vertex of the angle between the sides and flange in oblique relation thereto, and the slits in each side portion being disposed in approximate parallelism with each other and terminating within the material adjacent and at each side of said line.

35 6. A shoe counter of sheet material moulded in U-form to fit the heel end of a last and having its sides arranged to extend opposite the shank portion of a shoe and one edge portion thereof inturned to form a bottom engaging flange, each side portion of the counter having suitably spaced slits cut therein across the line of the vertex of the angle between the sides and flange, the sides of each slit being inclined towards the end of the side portion of the counter in which it is located from its inner side outward.

45 7. A shoe counter of sheet material moulded in U-form to fit the heel end of a last and having its sides arranged to extend opposite the shank portion of a shoe and one edge portion thereof inturned to form a bottom engaging flange, each side portion of the counter having a plurality of suitably spaced slits cut therein across the line of the vertex of the angle between the sides and flange, the portions of each slit at the opposite sides of said line extending divergent-

ly therefrom towards the middle of the counter and terminating in the material thereof, to form a series of tongues in each side portion which extend towards the end thereof in the direction of said line.

8. A shoe counter of sheet material moulded in U-form to fit the heel end of a last and having its sides arranged to extend opposite the shank portion of a shoe and one edge portion thereof inturned to form a bottom engaging flange, each side portion of the counter having a plurality of suitably spaced slits cut therein across the line of the vertex of the angle between the sides and flange, the portions of each slit at the opposite sides of said line extending divergently therefrom towards the middle of the counter and terminating in the material thereof, to form a series of tongues in each side portion which extend towards the end thereof in the direction of said line, said slits being cut obliquely through the material at an inclination to its surface to bevel said tongues on their inner sides.

9. A shoe counter of sheet material moulded in U-form to fit the heel end of a last and having one of its sides arranged to extend opposite the shank portion of a shoe and an inturned edge portion forming a bottom engaging flange, said side portion having slits cut therein across the line of the vertex of the angle between the side and flange and obliquely to the surface of the material.

10 10. A shoe counter of sheet material moulded in U-form to fit the heel end of a last and having one of its sides arranged to extend opposite the shank portion of a shoe and an inturned edge portion forming a bottom engaging flange, said side portion having a plurality of suitably spaced slits cut therein obliquely to the surface of the material and across the line of the vertex of the angle between said sides and flange, said slits being terminated in the material adjacent and at each side of said line.

115 11. A shoe counter of sheet material moulded in U-form to fit the heel end of a last and having one of its sides arranged to extend opposite the shank portion of a shoe and one edge portion thereof inturned to form a bottom engaging flange, the shank portion of said side portion having one or more slits cut therein at an inclination to the surface of the material and across the line of the vertex of the angle between the side and flange, the portions thereof at opposite sides of said line being extended convergently to said line and being terminated in the material adjacent thereto.

120 12. A shoe counter of sheet material moulded in U-form to fit the heel end of a last and having one of its side portions arranged to extend opposite the shank portion of a shoe and an inturned edge portion form-

ing a bottom engaging flange, the shank portion of said side portion having a plurality of suitably spaced slits cut therein at an inclination to the surface of the material and across the line of the vertex of the angle between the side and flange, the portions of each slit at the opposite sides of said line extending divergently therefrom in position to form a series of under cut tongues which extend in the direction of said line and are approximately bisected thereby.

10 In testimony whereof, I have signed my name to this specification.

GEORGE E. BRITTAIRN.
